(57) CLAIM

The ornamental design for a head for grooming brush, as shown and described.

DESCRIPTION

FIG. 1 is a perspective view of a head for grooming brush showing my new design;

FIG. 2 is a side elevation view thereof;

FIG. 3 is a top view thereof;

FIG. 4 is a bottom view thereof;

FIG. 5 is a front elevation view thereof; and,

FIG. 6 is a rear elevation view thereof.

The broken lines showing a handle, bristle plate, bristles and head support section are for illustrative purposes only and form no part of the claimed design.
